UNITED STATES PATENT OFFICE.

WILLIAM EGGERT, JR., OF BRIGHTWATERS, NEW YORK.

TOBACCO-LEAF-STRINGING MACHINE.

Application filed December 31, 1925. Serial No. 78,539.

This invention relates to tobacco leaf stringing machines of the class in which the required number of leaves is suspended in spaced apart relation and in which a needle 5 is adapted to pass through the stem ends of the leaves so as to draw a string there-through, with a view to so stringing the leaves that the ends of the string may be secured to a lath and the lath hung up in a 10 curing shed in the customary manner of curing leaves which have been pulled from the stalk as distinguished from doing so while the leaves are on the stalk. This method of handling tobacco for curing it is preferred 15 by the growers of fine leaf tobacco for use as high grade wrappers, as the leaves are held spaced apart on the lath substantially as in the machine by which they are strung, and it eliminates practically all waste which 20 is due to shed burn, rot or mold.

In machines of the class referred to, it is customary to suspend forty leaves of tobacco for the purpose of stringing them (of course the number could be varied), and such a 25 great number of leaves offers much resistance to the passage of the stringing needle there-through. Hence, one of the objects of the present invention is to provide an improved needle, for the purpose of which each needle 30 is provided with a long thin shank and a relatively short enlarged head which is provided with a barb or eye to receive the string, the length of the needle head being preferably only sufficient to take in three 35 leaves as the needle passes through the leaves, so that a minimum of resistance is offered by the leaves as the needle pierces them.

Another object of the invention is to provide 40 a tobacco stringing machine which is of simple construction while at the same time it is provided with the necessary and convenient means for guiding and reciprocating the needle, such means being preferably 45 constructed as hereinafter explained.

With these and other objects in view, my 50 invention consists of certain features of construction and combinations of parts to be hereinafter described and then claimed, with 55 reference to the accompanying drawings illustrating a preferred embodiment of the invention, in which

Fig. 1 is a side elevation of the improved machine, the middle portion being broken out so as to show the machine on a larger scale;

Fig. 2 is a plan of the machine shown in Fig. 1;

Fig. 3 is an enlarged vertical section of the needle sheath and of the machine; 60

Fig. 4 is an enlarged transverse section on the line 4—4 Fig. 1;

Fig. 5 is an enlarged transverse section on the line 5—5 Fig. 1, a leaf being shown in 65 broken lines;

Fig. 6 is an enlarged section on the line 6—6 of Fig. 3;

Fig. 7 is a side elevation of the needle also showing the butt member of the needle shank; and 70

Figs. 8 and 9 are transverse sections, respectively, on the lines 8—8 and 9—9 of Fig. 7.

The frame 10 of the machine may be of any suitable construction but it is preferred 75 that it take the general form of a beam, and it is provided with supports 11 which may be attached in any suitable manner to a table, wall or other main support, so that the frame 10 will be held at the desired height 80 from the floor.

The frame 10 is provided with a series of partitions 12 arranged equidistantly so as to provide a series of pockets 13 between them, and preferably the partitions extend in 85 straight alignment. The pockets 13 are open at the bottom and at the front of the machine so as to enable the stem ends of tobacco leaves to be introduced thereto. A series of aligned perforations 14 is provided 90 in the partitions 12, and slots 14^a open out from the perforations through the front edges of the partitions so as to provide open throats to permit withdrawal of the strung leaves. 95

Securing means 15 are preferably located in the pockets to provide means for suspending the tobacco leaves 16, such means being preferably in the form of impaling hooks which project from the corresponding side 100 of the partitions 12 transversely of the pockets, and in the embodiment of the invention shown these hooks extend towards the right hand of the attendant of the machine. Hence, when the leaves are impaled 105 on the hooks 15 they will hang from the right hand sides of the partitions 12. The hooks 15 are preferably in alignment in the pockets and are positioned directly beneath the perforations 14. 110

The present invention preferably includes an improved leaf piercing and stringing nee-

dle 17 which will pass through the leaves with a minimum of resistance, and to that end such needle comprises a thin elongated shank 18 and a relatively short enlarged head 19. The construction and shape of the needle is clearly shown in Fig. 7 and it will be seen that the rear portion of the enlarged head 19 gradually tapers to the considerably thinner shank 18, and that the other end of the needle is tapered to a point and is provided with a barb 20 so as to provide an open eye to receive a string. Preferably the length of the enlarged head 19 of the needle is just sufficient to take in, or pass at one time, only three tobacco leaves when the needle is passing through the leaves suspended by the machine. In this way a minimum resistance to the passage of the needle is imparted. Of course the perforations 14 in the partitions 20 are large enough to permit the passage of the enlarged head of the needle.

A suitable sheath 21 is preferably provided at the right hand end of the machine to receive the needle when withdrawn from the leaves, and this sheath extends in alignment with the series of perforations 14 in the partitions. The sheath 21 is provided with an elbowlike head 22 which carries a threaded bolt 23 that passes through a hole 24 in the frame of the machine, a nut 25 being threaded onto the bolt for rigidly securing the tubular head 22 in place. Preferably the sheath 21 telescopes onto the tubular head 22 and is secured rigidly thereto by a thumb screw 26. The bore of the tubular head 22 and the bore of the sheath 21 are in alignment, so that the two bores form a chamber into which the needle may be drawn.

The guide member 27 is fixed in the chamber of the sheath 21, preferably being pinched and held in position between the forward end of the sheath and the rear end of the tubular head 22. The hole through this guide is in alignment with the perforations 14. The shank of the needle is provided with a butt-member 28 which is adapted to be guided in the sheath 21 along a line back of or to the right of the needle guide 27, which guide also forms a stop against which the butt-member 28 may come in contact to prevent the entire withdrawal of the needle from the sheath.

In view of the extreme simplicity and manner of use and operation of the above described parts, the present invention lends itself most admirably to a very simple and efficient means of control and operation. To this end the frame of the machine may be provided with a bracket 29 having a socket 30, fixed rigidly to the rear end of the sheath 21, and bracket arms 31 and 32, the brackets 29, 31 and 32 preferably extending in the same direction. The operating means for the needle preferably comprises a flexible

cable 33 which is preferably composed of two connected sections, the cable being guided over a system of guide pulleys comprising pulleys 34, 35, 36, 37, 38, 39 and 40. The pulleys 35 and 36 are mounted respectively on the bracket arms 32 and 31; the pulleys 37, 38 are mounted on the main portion of the frame above the series of pockets; and the pulleys 39 and 40 are mounted on the bracket 29 at the rear end of the sheath. The pulley 34 is mounted in the elbow head 22, preferably just to the right of the series of pockets. The ends of the cable are firmly secured to the butt-member 28 of the needle, and the cable is led out through the bore of the elbow head 22 and trained in succession over pulleys 34, 35, 36, 37, 38, 39 and 40, the cable at this point being lead into the bore of the sheath 21. That portion of the cable which is located remote from the pockets 13 is provided with pins 41 and 42, which have right and left screw threads, respectively. Said pins being secured to cable ends 43, 44 which form the length of the entire cable which may be moved on a line substantially parallel with the direction of movement of the needle. The threaded pins 41 and 42 are connected preferably by means of a turnbuckle 45, so that the cable may be subjected to the desired tension and all slack therein taken up.

Briefly, the use and operation of the machine is as follows: The attendant of the machine inserts the stem ends of the tobacco leaves singly into the respective pockets 13 and impales the leaves on the hooks 15 so that the leaves, preferably forty in number, will hang in spaced relation at substantially equal distances apart. The suspending of the successive leaves may be done very quickly, one reason being that the walls of the successive pockets act as guides for the leaves when being introduced into the pockets. The leaves having been suspended from the frame, the attendant takes hold of the handle 45, furnished by the turnbuckle or the like, with his right hand and moves the handle from a point adjacent the pulley 35 in a straight line to the left so as to bring the handle to the position shown in Fig. 1. By this movement the portion 44 of the cable will act to pull the needle forwardly through the leaves, and the needle passes through with a minimum resistance because of the preferably used enlarged head thereon. When the needle is in the position shown in Fig. 1 its barb 20 will have passed through all of the leaves, and a string may be engaged with the barb as shown in Fig. 1, by the attendant making use of his left hand. The attendant now moves the handle 45 towards the right, which movement when complete will result in the needle pulling the string through all the leaves and to recede into the sheath 21. It is clear that

the portion 43 of the cable will then act to pull the butt-member of the needle and the needle itself towards the pulleys 39 and 40. The needle having thus drawn the string 5 through the leaves, the free end of the string may be disengaged from the barb of the needle and the string drawn towards the left so as to provide sufficiently long ends 10 of the string to enable them to be secured in the usual manner around the ends of a lath, which is then hung with the leaves on the beams provided therefor.

It will be seen that the reciprocating forward and backward movement of the needle 15 is preferably accomplished by the very simple expedient of the flexible cable, and that it is only necessary for the attendant to move the right hand which grasps the handle 45 to the left to cause a corresponding forward movement of the needle, and when the handle is moved to the right a corresponding movement is imparted to the needle, all in a very simple and efficient manner, requiring little exertion and skill on 20 the part of the attendant.

It is obvious that this invention may be modified in various ways without departing from the scope of the appended claims.

What I claim as new is:

30 1. In a machine of the class described, the combination of supporting means provided with a series of spaced partitions having aligned perforations, means for retaining the ends of articles in the spaces and for supporting the articles individually in spaced relation, and a needle movable in the said perforations, the needle being longer than the series of partitions and having a long slender shank and a relatively short 35 and enlarged head, the said head having a piercing point and a barb at its forward end, and the length of said head being such that during its movement through the perforations the head is always supported by at 40 least two of the partitions, and the length also being just sufficient to pass through a relatively few of the spaced articles simultaneously whereby to offer the maximum resistance to the passage of the needle, and 45 whereby a minimum resistance is offered by the other of such articles to the passage of said shank, and said head passing closely through some of said perforations at all times, thereby to assure the shank of the 50 needle against bending from the desired path of movement.

2. In a machine of the class described, the combination of a frame provided with a series of aligned pockets, hooks at corresponding sides of the respective pockets for impaling articles, and pointed toward one end of said series, and a needle longer than the series of pockets, and normally located away from that end of the series toward which the 55 hooks point.

3. In a machine of the class described, the combination of a frame provided with a series of aligned pockets, means for impaling articles and located in the pockets at corresponding sides thereof and pointed toward 70 one end of said series, the pockets having aligned perforations, an elongated sheath in line with the perforations and extending in the direction in which the impaling means extend, a needle longer than the series of 75 pockets and being normally guided into said sheath, the needle having a butt-member, and needle guide-member fixed transversely in said sheath and located back of the inner end of the sheath, and adapted to be engaged by the butt-member to prevent displacement of the needle entirely from the sheath.

4. In a machine of the class described, the combination of a frame provided with a series of aligned pockets having a series of aligned perforations, means for retaining the stem ends of tobacco leaves at the pockets, an elongated sheath in line with the perforations, a needle in the sheath and movable through the perforations, a needle guide adjacent the forward end of the sheath, a flexible cable having its ends attached to the rear end of the needle, a system of guide pulleys over which the cable is looped and trained, two of said pulleys being arranged laterally of the series of pockets and providing a length of cable laterally opposite to and substantially parallel with said series and to constitute an actuating portion, and a 90 handle on said actuating portion.

5. In a machine of the class described, the combination of a frame having means for suspending leaves in succession, a needle adapted to penetrate the leaves and to pass 105 a string therethrough, a system of pulleys mounted on the frame, and an operating cable attached to the needle and guided on said pulleys, a portion of the cable being arranged laterally of the series of pockets and provided with a handle which is movable in a line substantially parallel with the direction of movement of the needle.

6. In a machine of the class described, the combination of a frame having means for suspending leaves in succession, a needle adapted to penetrate the leaves and to pass a string therethrough, a system of pulleys mounted on the frame, and an operating cable attached to the needle and guided on said pulleys, a portion of the cable being arranged laterally of the series of pockets and provided with a turn-buckle to take up slack and put tension on the cable, the buckle being also arranged laterally of the series of pockets and serving as a handle which is movable in a line substantially parallel with the direction of movement of the needle.

7. A needle for stringing tobacco leaves, which comprises a long slender shank and 130

a relatively short and enlarged head, the said head having a piercing point and a barb adjacent and just back of said point, and extending toward the shank, for substantially the purposes set forth.

8. A needle for stringing tobacco leaves, which comprises a long slender shank and a

relatively short and enlarged head which is tapered to the shank, the said head also being tapered to a piercing point and having a barb adjacent and just back of said point, and extending toward the shank, for substantially the purposes set forth.

WILLIAM EGGERT, JR.
